UNITED STATES PATENT OFFICE.

JAMES M. TRIGGS, OF MORENCI, MICHIGAN.

COAL-CHUTE.

No. 833,352.

Specification of Letters Patent.

Patented Oct. 16, 1906.

Application filed May 23, 1906. Serial No. 318,286.

To all whom it may concern:

Be it known that I, JAMES M. TRIGGS, a citizen of the United States, and a resident of Morenci, in the county of Lenawee and State of Michigan, have invented certain new and useful Improvements in Coal-Chutes; and I do hereby declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to chutes of the class adapted to remain permanently secured within a window opening or casing and to combine both a closure for such opening and a chute for directing coal, wood, or the like therethrough.

20 The object of my invention is the provision of a simplified and improved construction of chute of this class, having a removable hopper portion, which is adapted to be entirely 25 inclosed within the chute when the door thereof is closed, placed in position to serve as a hopper for the chute-opening, or removed therefrom to convert it into a chute for wood or other bulky objects.

30 A further object of my invention is the provision, in combination with a chute, of a closure or door therefor which is adapted when raised to automatically lock itself in elevated position and to serve as a shield or 35 protection for the portion of the framework or wall immediately above the opening therein while coal or other matter is being discharged within the chute.

35 The invention is fully described in the following specification and shown in the accompanying drawings, in which—

Figure 1 is a perspective view of my improved chute in open position. Fig. 2 is a vertical section of a brick wall with my chute secured therein in similar section and in closed position, and Fig. 3 is a vertical section of a frame wall having the chute mounted in an opening therein with the door elevated and the hopper removed.

45 Referring to the drawings, 1 represents the wall of a building, which may be of brick, stone, wood, or other suitable construction and provided with an opening or window through which coal, wood, or other matter 50 may be discharged.

The device comprising my invention consists of the rectangular frame or casing member 2, which is of suitable size to fit around the margin of the opening provided in the wall 1 and is formed at its inner edge with the 60 rearwardly-projecting flange 3, which fits within the opening. Riveted or otherwise secured to this flange is the inner end of the chute portion 4, which extends inwardly and downwardly at an angle to give it the desired 65 slant and terminates at or near the inner side of the wall, as shown.

At the upper portion of the frame 2 are formed the two outwardly-projecting lugs 5, carrying the bearing-pins 6, to which the 70 ears 7 of the door 8 are hinged. The pins 6 project within slots 9 in the ears 7, thus enabling the door when raised substantially to vertical position to drop down slightly relative to said pins, so that the outer ends of the 75 ears 7 coact with the frame and prevent a lowering of the door, as shown in Figs. 1 and 3. Pivoted to an ear 10 near the lower inner edge of the door 8 is a hook 11, which is adapted when the door is closed to engage with the 80 inner edge of the contiguous portion of the flange 3 or with a ledge formed thereon, as shown in Fig. 2, thus preventing an unlocking of the door from without the building.

Normally inclosed within the chute 4 is 85 what may be termed a "hopper" 12. This hopper comprises the triangular side portions 13 and the curved bottom portion 14, the former being pivoted at their apexes or upper ends to the opposite side flanges of the 90 frame 2, near the tops thereof, as at 15. To enable the hopper to be readily removed from the pivots 15, the receiving-bearings therein are formed in L shape, with one end opening without the hopper side, as shown 95 at 16. This hopper is retained in inclosed position by the door 8 when closed, as shown in Fig. 2, and is retained in open position to act as a hopper for the chute by the provision adjacent the lower edge thereof of one or 100 more lugs or spurs 17, which are positioned to coact with the lower portion of the frame 2, as shown in Fig. 1. The slotted bearings 16 permit the hopper to be raised to enable these lugs or spurs to pass over the coacting 105 frame portion.

While I have shown and described for the purpose of illustration a particular form of chute and hopper therefor, I do not wish to restrict myself to this construction, as nu- 110

merous modifications thereof will be apparent to one skilled in the art.

With my construction of chute the hopper may be drawn out to the position as shown in Fig. 1 to adapt the chute for the reception of coal, potatoes, or other like matter, or it may be entirely removed from the chute, as shown in Fig. 3, when it is desired to discharge wood or the like therethrough. The raising of the door above the chute-opening also forms an advantageous feature thereof, as the woodwork or wall immediately above the opening is thereby protected from flying particles of the matter being handled.

Having thus described my invention, what I claim as new, and desire to secure by Letters Patent, is—

1. The combination with a chute, of a hopper portion pivoted thereto and adapted to be placed in operative or inoperative position relative thereto.

2. The combination with a chute, of a hopper portion removably pivoted therein adjacent its mouth and adapted to be placed in operative or inoperative position relative thereto.

3. The combination with a chute, of a triangular-shaped hopper removably pivoted therein and adapted to be entirely inclosed therein or drawn out to act as a hopper for the mouth of the chute.

4. The combination with a chute, of a door hinged to normally close the mouth thereof, and a member pivoted within the chute and adapted to be placed in inclosed position when the door is closed and be drawn out to act as a hopper therefor when the door is in open position.

5. The combination with a chute, of a door and a hopper each having separate pivotal connection therewith, and the latter being

locked in inoperative position therein by a closing of the door.

6. The combination with a chute, of a door adapted to be elevated above the mouth thereof when open, and a member normally inclosed within the chute and adapted to be drawn out to act as a hopper for its mouth when the door is open.

7. The combination with a chute, of a door pivoted above its mouth and having means associated with its pivot for automatically locking it in elevated position.

8. The combination with a chute, of a member pivoted within and adjacent the top of the mouth thereof, said member being adapted to be swung outwardly relative to the chute to act as a hopper therefor and provided with slotted bearings having one end open to permit a removal of the member from its pivot.

9. In combination, a chute, a door hinged at the top of the chute-mouth and having slotted bearing-ears for the purpose described, a hook on the door for locking within the mouth of the chute when the door is closed, and a hopper comprising triangular side portions and a curved base portion connecting the side portions and provided with spurs for coacting with the lower outer portion of the chute-frame when the hopper is in open position, said side portions being pivoted within the chute-mouth and having open slotted bearings, substantially as described.

In testimony whereof I have hereunto signed my name to this specification in the presence of two subscribing witnesses.

JAMES M. TRIGGS.
